US0D1033626S

(12) **United States Design Patent** (10) **Patent No.:** **US D1,033,626 S**
(45) **Date of Patent:** **** Jul. 2, 2024**

(54) **DISPENSER FOR BARRIER MATERIALS**

(71) Applicant: **Sano Curatio, LLC**, Henderson, NV (US)

(72) Inventors: **Norman Tien-Yo Chien**, Sierra Madre, CA (US); **Richard Alan Swartzbaugh**, Henderson, NV (US)

(73) Assignee: **SANO CURATIO, LLC**, Henderson, NV (US)

(**) Term: **15 Years**

(21) Appl. No.: **29/809,528**

(22) Filed: **Sep. 28, 2021**

(51) LOC (14) Cl. **24-01**

(52) U.S. Cl.

USPC **D24/108**; D24/232

(58) **Field of Classification Search**

USPC D24/107, 108, 169, 183–187, 216–219, D24/234; D34/1, 12, 19, 25; D12/129

CPC A61L 2/28; A61L 2202/24; A61L 2202/17; A61L 2202/14; A61B 19/34

(57) **CLAIM**

The ornamental design for a dispenser for barrier materials, as shown and described.

DESCRIPTION

FIG. 1 is a perspective view of a dispenser for barrier materials;

FIG. 2 is a front view of the dispenser for barrier materials shown in FIG. 1;

FIG. 3 is a rear view of the dispenser for barrier materials shown in FIG. 1;

FIG. 4 is a left-side view of the dispenser for barrier materials shown in FIG. 1;

FIG. 5 is a right-side view of the dispenser for barrier materials shown in FIG. 1;

FIG. 6 is a top view of the dispenser for barrier materials shown in FIG. 1; and,

FIG. 7 is a bottom view of the dispenser for barrier materials shown in FIG. 1.

The broken lines depict portions of the dispenser for barrier materials that form no part of the claimed design.

1 Claim, 7 Drawing Sheets
